CHEMICAL HEATING PAD

William H. H. Davis and Leon Markel, San Francisco, Calif., assignors to United States Appliance Corporation, San Francisco, Calif., a corporation of California

Application June 27, 1938, Serial No. 216,022

7 Claims. (Cl. 132—36.2)

This invention relates generally to chemical heating pads such as are suitable for permanent hair waving operations, and to methods for their manufacture. More particularly it is concerned with the construction and manufacture of permanent waving pads making use of an exothermic chemical reaction for generating the requisite heat required for a waving operation.

Small chemical heating devices intended to be used to generate a predetermined amount of heat, and then to be discarded, have come into wide commercial use for the purpose of permanently waving hair. As disclosed in Reynolds application Serial No. 176,229, entitled "Chemical heating pad for permanent hair waving", one type of device for this purpose makes use of an inner flexible assembly, consisting of sheets of absorbent material in contact with one or more sheets of aluminum foil. At the time the pad is used the inner assembly is saturated with a chemical solution capable of exothermic reaction with the aluminum foil, and as applied to the wound hair the inner assembly is enclosed within a protective wrapper. One characteristic of such a chemical pad is that all of the water soluble chemical supplied for the reaction, is contained within the applied chemical solution. The pad assembly contains no reactive chemical whatsoever, except the aluminum foil, and therefore it is totally inert before the solution is applied.

It is an object of the present invention to provide a chemical pad of the above character, improved particularly with respect to the manner of forming the protective wrapper, whereby application of the chemical solution and use of the pad is greatly facilitated.

A further object is to improve upon the manner in which the material forming the outer wrapper is applied to the inner assembly, to form a self retaining envelope, without the use of adhesive or supplemental retaining means.

Further objects of the invention will appear from the following description in which the preferred embodiment of the invention has been set forth in detail in conjunction with the accompanying drawing.

Referring to the drawing:

Fig. 1 is a perspective view illustrating the parts of our pad, in its preferred form, before folding of the same.

Fig. 2 illustrates the parts of our pad construction after one folding operation, namely the folding of the inner assembly and the outer wrapper sheet upon a common fold line.

Fig. 3 illustrates one folding operation of the

end edges of the wrapper, and Fig. 4 illustrates a second folding operation, whereby there is produced an envelope enclosing the inner assembly.

Fig. 5 is a perspective view illustrating the assembly of Fig. 4 while a predetermined amount of chemical solution is being applied.

Fig. 6 is a cross-sectional detail on an enlarged scale taken along the line 6—6 of Fig. 4.

Fig. 7 is a side elevational view illustrating the complete pad with the flap of the envelope closed. 10

Fig. 8 is an enlarged cross-sectional view similar to Fig. 6, but illustrating a modification.

Fig. 9 is a side elevational view partly in cross-section illustrating the manner in which my pad can be used in a permanent hair waving operation. 15

The pad construction as illustrated in the drawing consists generally of an inner assembly 10, together with an outer wrapper 11. The inner assembly 10 can be formed as disclosed and claimed in co-pending application Serial No. 20 210,436, filed May 27, 1938. Briefly, a suitable construction for the inner assembly 10 can consist of a plurality of sheets of absorbent asbestos paper 10b with sheets 10c of aluminum foil interposed between the sheets of paper. The superposed sheets are passed through a suitable perforating appliance whereby perforations 12 are formed over the entire area of the sheets, in order to facilitate reaction of chemical solution with the aluminum foil, and in order to facilitate ready absorption of chemical solution. 25

The outer wrapper 11 preferably consists of a sheet 13 of metal foil, having its inner surface covered by the parchment or wax paper 14. Interposed between the outer wrapper 11 and the 35 inner assembly 10 we prefer to employ a sheet 16 of absorbent paper, such as paper towelling.

In manufacturing pads in quantities the parts just described can be superposed as illustrated in Fig. 1. The next operation is to fold both the 40 flat inner assembly 10, and the outer wrapper 11, along the common fold line 17. After making this fold the parts appear as illustrated in Fig. 2.

The next operation serves to fold over the projecting end margins 18, in order to form the outer 45 wrapper into an envelope enclosing the folded inner assembly 10. To produce a construction as illustrated in detail in Fig. 6, we use a double folding operation, that is, the end margins 18 are folded over at least twice. The first folding operation can be along the fold lines 19, as illustrated in Fig. 3, and the next folding operation can be along the fold lines 21, to produce a completed assembly such as illustrated in Fig. 4. 50 Thereafter the projecting flap 22 can be closed by 55

folding down on the fold line 23, to produce the final marketable assembly packet as illustrated in Fig. 7.

Instead of using such a double fold for the end margins 19, these margins can be rolled upon themselves as indicated at 24 in Fig. 8. Which ever method is employed there is formed, as previously pointed out, an envelope from the outer wrapper, and this envelope can be opened to permit access to the inner assembly, by swinging open the projecting flap 22.

The pad is used with a chemical solution capable of exothermic reaction with the aluminum foil. It is desirable to employ a chemical solution containing a copper salt like copper sulphate, together with an oxidizing agent such as sodium chlorate, a salt like aluminum sulphate capable of speeding up the reaction, and a salt like ammonium chloride capable of controlling the hydrogen ion concentration of the solution during the reaction, whereby when the reaction is completed the remaining solution is substantially neutral. One solution which can be employed is as follows:—

	Grams
Hydrated copper sulphate	3
Sodium chlorate	17
Hydrated aluminum sulphate	½
Ammonium chloride	½
30 Sufficient water to make 30 cc. of solution.	

A suitable solution such as referred to above is supplied for use by the operator, and constitutes all of the chemical required for exothermic reaction with the aluminum foil. When an operator desires to use the pad for a hair waving operation, the flap 22 is swung to open position substantially as illustrated in Fig. 5, and by applying manual pressure to the two end edges of the pad, the folded side portions 10a of the inner assembly 10 are bulged apart. A given amount of the chemical solution is now introduced into a suitable measuring appliance, such as a syringe 26, and the nozzle of this syringe is then introduced into the open edge of the pad between the side portions 10a of the inner assembly, and the solution then discharged into the pad. The first effect is to somewhat flood the interior of the pad, but in a relatively short interval the solution is taken up by the absorbent material of the inner assembly 10, whereby the solution is brought into intimate reactive contact with all exposed surfaces of the aluminum foil. The distended sides of the pad are then forced together and after closing down the flap 22, the pad is bent over a curler 27 upon which hair has been wound (Fig. 9). As will be understood by those skilled in the art this curler may be mounted upon a suitable protector 28. The strand of hair is usually moistened with a suitable waving solution before the pad is applied, and the pad can be retained in place by a suitable spring clip 29.

During a waving operation and as the exothermic reaction proceeds between the chemical solution and the aluminum foil of the inner assembly 10, some water vapor is generated within the pad, and must be permitted to escape in order to avoid internal pressure and resultant bulging. With our construction such vapor may escape from different portions of the pad, as for example from the folded or rolled end margins 18, although the pad is adequately closed with respect to escape of chemical solution. This is because the interposed sheet 16 of absorbent paper enables escape of vapor, without however permitting escape of

liquid. Any liquid tending to escape or seep from the inner assembly 10, is absorbed by the paper 16.

It is desirable to employ asbestos paper in constructing the inner assembly 10, in order to avoid a fire hazard. Such a fire hazard is involved not only because of the use of an oxidizing reagent in the chemical solution, but also because in the event a pad is not immediately applied to the hair, after solution is introduced into the same, excessive internal heat attained can not seriously burn or char the inner assembly. The relatively small amount of cellulose fiber afforded by the paper towelling 16, or by the parchment liner 14, is insufficient to cause any appreciable amount of charring or fire hazard.

In addition to the attributes described above, the double folding described, or the rolling of the end margins 18, makes it unnecessary to employ additional retaining means to hold the wrapper intact while the pad is being shipped and used. In other words such a construction affords a stiffness for the end edges of the wrapper, and a type of closure for the end edges which will remain intact while the pad is being handled and while the flap 22 is being opened and closed.

The construction of the pad, which affords an open longitudinal edge, for introduction of the solution as described above, is desirable from the standpoint of convenience of operation. Also as previously mentioned because such introduction of chemical solution causes initial flooding of a part of the aluminum foil. Such initial flooding has been found advantageous in initiating chemical reaction between the chemical solution and the aluminum foil.

We claim:

1. In a chemical heating pad for permanent hair waving operations, an outer protective envelope having a closure flap and an open longitudinal edge closed by folding down the flap, and an inner assembly within the envelope adapted to be moistened with a chemical solution for an exothermic reaction, said assembly being accessible for introduction of solution through said open longitudinal edge.

2. In a chemical heating pad for permanent hair waving operations, an outer protective envelope having a closure flap and an open longitudinal edge closed by folding down the flap upon the body of the envelope, and an inner assembly within the envelope adapted to be moistened with a chemical solution for an exothermic reaction, said inner assembly consisting of sheets of absorbent material in intimate contact with sheets of metallic foil, said metallic foil being adapted for exothermic reaction with chemical solution.

3. In a chemical heating pad for permanent hair waving operations, an outer protective envelope having a closure flap and a longitudinal open edge closed by folding down the flap upon the body of the envelope, and an inner assembly within the envelope adapted to be moistened with a chemical solution applied through said open edge, said chemical solution being capable of an exothermic reaction with said inner assembly, said inner assembly consisting of a sheet of absorbent material in intimate surface to surface contact with a sheet of metallic foil, the metallic foil being capable of exothermic reaction with chemical solution, said assembly being relatively flat and folded upon itself.

4. In a chemical heating pad for permanent hair waving operations, an outer protective envelope having a closure flap extending from one longitudinal edge of the same, said longitudinal

edge of the envelope being open when the flap is extended and closed by folding down the flap upon the body of the envelope, the opposite parallel longitudinal edge of the envelope being closed, an inner assembly within the envelope adapted to be moistened with a chemical solution for carrying out an exothermic reaction, the open longitudinal edge of the envelope enabling application of said solution, said inner assembly including a sheet of absorbent material in intimate contact with a sheet of aluminum foil, both said sheets forming a substantially flat assembly, with the sheets doubled upon themselves, said assembly being disposed within the envelope with its fold line disposed adjacent the closed longitudinal edge of the envelope and with the other longitudinal edge of the assembly substantially coincident with the open edge of the envelope.

5. In a chemical heating pad for permanent hair waving operations, an inner relatively flat assembly consisting of sheets of absorbent material together with sheets of metallic foil, said sheets being in intimate surface to surface contact, the absorbent material being adapted to be moistened with a chemical solution capable of 10 exothermic reaction with the metallic foil, a protective wrapper sheet folded about said assembly, the wrapper being folded first over one longitudinal edge of the assembly, the end edges of the 15 wrapper being folded at least twice to form an envelope, and the remaining flap being foldable over the assembly to form the completed wrapper.

6. In a chemical heating pad for permanent hair waving operations, an inner assembly capable of being moistened with chemical solution for carrying out an exothermic reaction, said inner assembly being substantially flat and rectangu- 20

lar in contour and consisting of a sheet of absorbent material together with a sheet of metallic foil in intimate surface to surface contact with the absorbent material, the metallic foil being capable of exothermic reaction with the chemical solution, and a protective wrapper sheet disposed about the inner assembly, said wrapper consisting of a sheet of flexible material rectangular in contour before being folded, and folded about the inner assembly to form an envelope having an 25 extending flap to close over one longitudinal edge of the envelope, the end edges of the envelope being formed by a double folding of end margins of the wrapper material, thereby forming a self retaining envelope.

7. In a chemical heating pad for permanent hair waving operations, an inner assembly capable of being moistened with chemical solution for carrying out an exothermic reaction, said inner assembly being substantially flat and rectangular 30 in contour and consisting of a sheet of absorbent material together with a sheet of metallic foil in intimate surface to surface contact with the absorbent material, the metallic foil being capable of exothermic reaction with the chemical solution, and a protective wrapper sheet disposed about the inner assembly, said wrapper consisting of a sheet of flexible material rectangular in contour before being folded, and folded about the inner assembly to form an envelope having 35 an extending flap to close over one longitudinal edge of the envelope, the end edges of the envelope being formed by rolling the material of the wrapper upon itself, thereby forming a substantially self sustaining envelope.
